UNITED STATES PATENT OFFICE.

MARGARET L. GARRISON, OF NEDERLAND, COLORADO.

DESIGN FOR A CROCHET WORK-BASKET.

47,557.

Specification for Design.

Patented July 13, 1915.

Application filed May 21, 1915. Serial No. 29,673. Term of patent 14 years.

To all whom it may concern:

Be it known that I, MARGARET L. GARRISON, a citizen of the United States, residing at Nederland, in the county of Boulder and State of Colorado, have invented a new, original, and ornamental Design for a Crochet Work-Basket, of which the following is a specification, reference being had to the accompanying drawing, forming part thereof.

The figure is a perspective view of a crochet work basket, showing my new design.

I claim:—

The ornamental design for a crochet work basket, as shown.

MARGARET L. GARRISON.

Witnesses:

W. L. TANNER,
R. H. CRAWFORD.
